J. J. Crawford,

Steam Cloth Press.

No. 90,893.

Patented Nov. 16, 1869

FIG. 2.

FIG. 3.

FIG. 4.

INVENTOR.
John J. Crawford.

WITNESSES.
John Houston,
R. T. Rawson.

United States Patent Office.

JOHN J. CRAWFORD, OF GLASGOW, SCOTLAND.

Letters Patent No. 96,893, dated November 16, 1869.

IMPROVEMENT IN STEAM CLOTH-PRESSES.

The Schedule referred to in these Letters Patent and making part of the same.

To all whom it may concern:

Be it known that I, JOHN J. CRAWFORD, of Glasgow, Scotland, but now a resident of Lowell, county of Middlesex, and State of Massachusetts, have invented new and useful Improvements in a Device for Operating Steam-Plates in Cloth-Presses; and I do hereby declare that the following is a full and exact description thereof, reference being had to the accompanying drawings, and to the letters of reference marked thereon.

The nature of my invention consists in providing a suitable device for cloth-presses, whereby steam finishing-plates may be applied to the same, and operated independently from each other, as desired.

To enable others skilled in the art to make and use my invention, I will proceed to describe its construction and operation.

Figure 1 represents a front elevation of a cloth-press, with my improved device attached.

Figure 2 represents an end view.

Figures 3 and 4 represent details of the same.

Similar letters in the different figures indicate corresponding parts.

In the construction of my device, *a* represents the base of the press, and *b* the top part, in the centre of which is secured a nut, in which operates the screw *c*, said screw connecting with the follower *d*, in the usual manner.

The base *a* and top *b* of the press being connected and secured together by means of the columns *e e e e*, which also serve as guides for the follower *d* and steam finishing-plates *fff*.

Pivoted to each corner of the follower *d*, on its outside, are the movable racks *g g g g*, which are provided with steps or notches *h h h*, on which rest the fingers *i i*, which are secured to or formed on the ends of the plates *fff*.

These movable racks *g g g g*, I form in a T-shape, although they may be formed in different shapes, as required, and located in different positions, they operating in sockets *j j j j*, which correspond, in size and shape, with the size and shape of the racks *g g g g*, thus serving as a guide for the same.

These sockets are secured to the floor, or to the bottom part of the press *a*, as may be required by the operator.

In the operation of my device, the same being designed and secured to the common hand and power-presses that are operated from the top, by a screw or

screws, *c*, the follower *d* is raised to its highest point of elevation, carrying with it the plates *fff*, by means of the racks *g g g g*, with steps *h h h*, and fingers *i i i*, these racks being guided by the sockets *j j j j*, which also keep the plates in their required position with each other.

When thus raised, the operator fills the space, as desired, between the base *a* and the bottom plate *f*, said plate having been previously raised to any height desired, and secured, which gives sufficient room for filling the same. When filled, the plate previously raised is let back to its former position, after which each plate *f* is filled, in its turn, by a similar manner, until the entire press is filled, each plate being raised independent from each other, which greatly facilitates the operation of filling.

When thus filled, the required pressure is given to the same, after which it is subjected to the steam-finishing process, as desired. The pressure is then removed by means of the screw *c*, raising the entire lot of plates *fff*, with their contents of finished material, to the highest elevation, and the material is removed easily and quickly, as the material, after going through this process, takes up but about one-half the space as it did before being operated upon.

The object of my device being to apply the same to this class of presses, and supply them with steam-finishing plates, which at the present time are provided with plates that are heated and then placed in the press by hand, whereby, with the other devices for operating steam-plates, in order to furnish the same, an entire new press has to be furnished, in order that it may be effective, also at a great cost, while with my simple device, the main part of the old press is retained, furnishing the device which is more effective, and at a much less cost.

I do not claim, broadly, the stepped racks for supporting the plates or platens, for racks of this construction I know to be old; but

What I do claim and desire to secure by Letters Patent, is—

The combination of the follower or plunger *d*, movable racks *g*, and sockets *j*, when said parts are constructed and arranged to operate as and for the purpose herein shown and described.

JOHN J. CRAWFORD:
